MULTIPLE-EXPANSION PISTON STEAM
ENGINE

Willi Rieger, Kassel-Wilhelmshöhe, Germany

Application February 26, 1937, Serial No. 128,005
In Germany March 3, 1936

3 Claims. (Cl. 121—102)

This invention relates to a multiple-expansion piston steam engine provided with a speed-change gearing between the crank shaft of the high-pressure stage and a crank shaft of a lower stage. With a known engine of this type a spur-wheel gearing is inserted between two crank shafts lying side by side. In contradistinction thereto the crank shafts are, in the present invention, arranged in a line and are connected with one another by planet-gearings having a corresponding ratio, whereby it is rendered possible to arrange the engine upon a frame of the usual construction.

The invention is illustrated diagrammatically and by way of example on the accompanying drawing on which is shown a constructional form of an engine designed according to this invention and on which Figure 1 is a front view of the engine, the change-speed gearing and the shaft bearings being, however, drawn in axial section. Figure 2 is a vertical transverse section through this engine in the line II—II of Fig. 1, and Figure 3 is a representation similar to Fig. 1, but provided with two change-speed gearings, these latter and the shaft-bearings being again drawn in axial section.

Referring to the figures, 1 denotes the high-pressure cylinder, 2 the medium-pressure cylinder, and 3 the low-pressure cylinder. I have abstained from entering into details of the engine as it is of a known design.

In Fig. 1 the crank shaft 4 of the high-pressure stage and the crank shaft 5 of the medium-pressure stage are rigidly connected with one another so that they rotate with the same speed. Between the crank shafts 4 and 5 on the one hand and the crank shaft 6 of the low-pressure stage on the other hand is inserted a planet-wheel gearing 7 of the sun type which likewise need not be described in detail, as it is of a known design. The ratio of the gear depends upon the size of the cogwheels of the same.

Supposing, the ratio of gearing amount to 1:4, so that the crank shaft 6 of the low-pressure stage makes 800 revolutions per minute if the number of revolutions of the shafts 4 and 5 amounts to 200 per minute, and supposing further that the ratio of expansion between the three cylinders be 1:3.7:60. With the usual construction of engines of the type in question, in which the three crank shafts rotate with the same speed, viz. 200 in the above example, the medium-pressure cylinder would have to be designed with a diameter of 240 mm. and the low-pressure cylinder would have to be designed with

a diameter of 970 mm. which is, however, so large that it is practically out of the question to build such an engine. But if, according to this invention, 800 revolutions per minute are used in the low-pressure stage, the diameter of the low-pressure cylinder will amount to only 485 mm. which is a very acceptable size for this cylinder.

In the modification shown in Fig. 3 all three crank shafts rotate with different speeds of revolution. Between the shaft 8 of the high-pressure stage and the shaft 9 of the medium-pressure stage is inserted the planet-wheel gearing 10, and between said shaft 9 and the shaft 12 of the low-pressure stage is inserted the planet-wheel gearing 13. The low-pressure stage 15 is divided into two low-pressure cylinders 3, 3. It is assumed that the planet-wheel gearings 10, 13 have a ratio of 1:1.5:2. With a number of revolutions of 300 in the high-pressure stage is obtained in the medium-pressure stage a number of revolutions of 450 and in the low-pressure stage a number of revolutions of 600. In accordance therewith, the diameter of the high-pressure cylinder being supposed to be 100 mm., the diameter of the medium cylinder will be 155 mm. and the diameter of each of the low-pressure cylinders will be 390 mm.

The work done may be drawn from the high-pressure side of the engine or from the low-pressure side of the same, just as requisite in a given case. In Fig. 1 one half of a coupling 14 is secured to the high-pressure shaft 4 and in Fig. 3 one half of a coupling 15 is affixed to the low-pressure shaft 12 of the engine.

I claim:

1. A reciprocating steam engine having a plurality of expansion stages comprising a plurality of linearly aligned crankshafts each being common to at least one stage and different from a crankshaft common to at least one other stage, and a sun type planetary gear transmission system connecting at least one of said crankshafts to an adjacent linearly aligned crankshaft for permitting the crankshafts of the various stages to rotate at different relative speeds.

2. A steam engine as in claim 1, bearings on said crankshafts, a bearing supporting frame having linearly aligned bearings thereon, said frame supporting said crankshafts and bearings.

3. A steam engine as in claim 1, said stages comprising a high-pressure, a medium-pressure, and a low-pressure stage, a crankshaft for each stage, and a planetary gearing connecting each two adjacent crankshafts.

WILLI RIEGER.
